REMOVABLE HOOD FOR A DRYING CYLINDER
Edgar J. Justus and Loyal H. Hess, Beloit, Wis., assignors
to Beloit Corporation, a corporation of Wisconsin
Filed Oct. 13, 1960, Ser. No. 62,433
2 Claims. (Cl. 34—114)

The present invention relates broadly to impingement air drying of sheet materials, and is more particularly concerned with a novel hood structure especially well-adapted for use with paper drier drums or cylinders and having as one feature thereof a unitary air impingement chamber and air exhaust means therein providing a compact structure of high drying efficiency.

Numerous attempts have been made in the past to develop a relatively simple hood arrangement for the accelerated drying of paper and related web materials by the use of high velocity-temperature air which is impinged upon the web material so as to penetrate the boundary film layer of vapor which adheres thereto and which normally diminishes by vapor contact the effect of drying. In many structures complex ductwork is utilized, resulting in heat energy losses and the necessity of excessive quantities of insulation. Other structures known to the art are not readily adapted to existing drying apparatus, while in others complex mechanisms are employed to raise and lower the hood relative to the drying cylinder. In all of these, it has been impossible to package all components within the hood or at least in close direct connection thereto, with the result that the prior art hoods have become unduly complex and lacking in a high order of drying efficiency.

It is accordingly an important aim of the present invention to provide a drying apparatus and method which overcomes the noted and other disadvantages of the prior art.

Another object of this invention lies in the provision of a hood structure for location in partial encircling relation to a drying cylinder, and which features a unitary air impingement chamber and air exhaust means therein permitting maximum drying efficiencies and the packaging of all or essentially all components within the hood itself.

Still another object of the instant invention is to provide a hood construction wherein the hood mouth mounts a unitary air supply air exhaust assembly desirably comprised of a pair of spaced curvate plate members mounting a plurality of spaced open-ended exhaust tubes in communication with the hood interior to direct moisture-laden air thereto, the space between the plate means communicating with air circulation means and the plate means more closely adjacent the drying drum being passaged to provide a plurality of shaped nozzle openings whereby drying air is impinged against the web in a direction substantially normal thereto and is then withdrawn through the exhaust tubes by the air circulation means for return thereto after passage against air heating means.

A further object of this invention is to provide a hinged hood arrangement embodying hood elevating and lowering means of high reliability, rapid action and devoid of structure limiting the degree of wrap of the hood with respect to the drying cylinder.

An even further object of this invention lies in the provision of hood means supported adjacent a drying cylinder, means defining an air discharge chamber extending across and along the mouth of the hood means and being passaged at a plurality of spaced points to provide nozzle openings therein, means in the chamber providing a plurality of individual moisture-bearing air flow paths from the web material to the interior of the hood means, and means for circulating air into the chamber and through the nozzle openings therein into im-

2

pingement with the paper web and thereafter in generally a reverse direction along the moisture-bearing air flow paths to the hood interior and back to the chamber.

Other objects and advantages of the invention will become more apparent during the course of the following description, particularly when taken in connection with the accompanying drawings.

In the drawings, wherein like numerals designate like parts throughout the same:

FIGURE 1 is a more or less diagrammatic view of a drier section of a paper machine and embodying therein drying means constructed in accordance with the principles of this invention;

FIGURE 2 is a fragmentary plan view of a preferred form of bottom impingement plate used in the hood structure of this invention;

FIGURE 3 is a fragmentary end view of the instant drying apparatus and showing one form of hood pivoting means which can be employed;

FIGURE 4 is a vertical sectional view through approximately one-half of the hood to illustrate further details thereof;

FIGURE 5 is a sectional view of the hood taken substantially along the line V—V of FIGURE 4;

FIGURE 6 is a sectional view of the plate means of FIGURE 2 to more fully illustrate the nozzle openings therein and passage for reception of an exhaust tube mounted in the manner of FIGURES 4 and 5; and

FIGURES 7 and 8 are detail views of actuating means which may be utilized to raise and lower the hood with respect to the drying cylinder.

Referring now to the drawings, there is shown somewhat diagrammatically in FIGURE 1 a dry end section 10 of drying apparatus of a paper machine with which the instant invention is of important application. The dry end section 10 comprises a first row of horizontally aligned drying cylinders or drums 11a-d of which four are shown in the illustrated exemplary embodiment, and a second row of horizontally aligned drying cylinders 12a-d staggered with respect to the drying drums 11 of the first row. A web of paper W passes alternatively about the drying cylinders 11 and 12, and is maintained in contact with the surfaces of the drying cylinders 11a and 11b by a felt 13 and against the surfaces of the drying drums 12a-d by a felt 14. A suitable number of rollers 15 are arranged to guide the felt 13, and rollers 16 guide the felt 14. The drying arrangement as thus far described will be recognized as of essentially conventional construction, and the general practice in the art is to wrap the web W about the drying cylinders 11 and 12. However, cylinders are not at all times required, and the instant invention can be practiced utilizing a hood positioned with its mouth portion relatively closely adjacent a paper web advanced along a generally straight line, rather than serpentine, path.

Drying apparatus generally designated by the legend A and as constructed in accordance with the principles of this invention, comprises a pair of essentially identical hingedly connected hood sections 20a and 20b each having a length preferably coextensive with the width of the web W, and together extending a sufficient distance about the cylinder or drum 11c to be coextensive with the wrap of the web W during travel along the circumferential portion of the rotatable drum 11c. Illustratively, the extent of wrap of the web on the drum circumference is approximately 180°.

The hood sections 20a and 20b are essentially identical as stated, and accordingly, only the details of a single hood section (20b) will be described in the material now to follow.

The hood section 20b shown in FIGURES 4 and 5 comprises a first body portion 21 defining therewithin an

exhaust chamber 22 and a pair of second housing portions 23 and 24 connected to opposite ends of the first housing portion 21 and defining interiorly air supply chambers 25. The first housing portion 21 is provided at opposite ends with a pair of generally arcuate wall portions 26 and 27 to which are connected axially extending and generally similarly shaped top wall portions 26a and 27a. Illustratively, each of the wall portions 26a and 27a may extend approximately one-fourth of the axial length of the drying cylinder 11c, and extending generally radially from the wall portions 26a and 27a are a pair of axially spaced wall portions 26b and 27b which mount a tubular exhaust duct portion 28 communicating with the air supply chambers 25.

Connected to the exhaust conduit 28 and providing the outer wall structure for the exhaust chamber 22 is a downwardly inclined wall portion 29 having an inwardly turned wall section 29a, while at the opposite end thereof the wall portion 29 has an upwardly inclined wall section 29b. Connecting with the wall section 29b is an upwardly inclined wall portion 30 and extending therefrom in the direction of the vertical centerline of the drier drum 11c is a wall portion 31. At the opposite end of the wall portion 31, on the other hand, there is provided a downwardly turned wall section 31a providing a surface for connection of the two hood sections 20a and 20b. The described wall sections are of course generally coextensive with the width of the web W wrapping the drying cylinder 11c, and as appears in FIGURES 4 and 5, the wall sections may be provided by a pair of spaced sheet metal members. As well, between the sheet metal members there is desirably located insulation means 32 to minimize heat losses from within the exhaust air chamber 22.

To provide access to the hood interior the outer wall section 29b may be hingedly connected to the wall section 30 may be constructed to provide a further access opening, as indicated at 30a. A further access opening may be provided in the wall section 29, as indicated at 29c, and this door may be hinged to control the extent of opening so that the amount of make-up air admitted therethrough may be regulated. As appears in FIGURE 4, the exhaust air chamber wall portions 26b and 27b may be apertured as at 33 to provide exhaust air outlets. In the manner known to the art, the exhaust openings 33 may be controlled by damper means in the form of a shiftable plate member or equivalent means.

The air supply housings 23 and 24 are essentially identical, and accordingly, the description will be particularly directed to the housing portion 23 shown in section in FIGURE 5. In the description of the air supply housing 23 now to follow, where applicable like numerals with the suffix "a" appended are applied to like parts of the air supply housing 24.

The air supply housing comprises first a sheet metal housing portion 46 connected to the exhaust chamber wall portion 26a. The housing portion 46, two of which are provided at opposite ends of each hood section 20a and 20b, is connected to a shroud member 35 enclosing blower or fan drive means 36, which is as illustrated a suitable drive motor. The motor means 36 is provided with shaft means 37 mounting pulley means 38 about which is trained belt means 39 also received about pulley means 40 on shaft means 41 mounting fan means 42 at the opposite end thereof. The shaft means 41, as appears in FIGURE 5, is journaled in suitable bearing means 43 and 44. As well, to support the bearing means 43 and 44 shelf means 45 are provided.

The fan or air recirculation means 42 is mounted within the housing portion 46 which in turn receives at its lower end a generally radially extending air supply conduit 47 communicating with an air discharge chamber generally designated by the numeral 48.

The air discharge chamber provided in accordance with the novel concepts of this invention includes top and bottom plate means 49 and 50 of arcuate shape when

viewed endwise and extending essentially entirely across the width of the web W wrapping the drying cylinder 11c. Each hood section 20a and 20b is equipped with a pair of radially spaced plate means 49 and 50 of essentially identical construction and each pair of plate means extends along approximately 90° of the circumference of the cylinder 11c.

The spaced plate means 49 and 50 may be welded at opposite ends of the two-piece end walls 26 and 27 of the hood sections, and if desired, brace means 51 (FIGURE 10) 4) may be welded to the top plate member 49 and to the exhaust chamber wall portions 26b and 27b. The top plate means 49 is passaged at spaced locations along its length to receive the lower ends of the air supply conduits 47, and radially inwardly of the lower ends of the conduits 47 and generally centrally between the two plate means 49 and 50 are baffle or diverter means 52 functioning to evenly and thoroughly distribute the air flow between the two plate members 49 and 50.

Each of the plate means 49 and 50 is passaged to receive tubular exhaust means 53, each of which is desirably provided with an outwardly flared discharge portion 54 lying against the upper plate member 49 to facilitate welding thereto. Each of the plate members 49 and 50 are passaged to receive therein opposite ends of the exhaust tubes 53, and a preferred configuration for the bottom impingement plate 50 appears in FIGURE 2. In a typical application wherein the plate 50 has a thickness of one-quarter inch, a width of six feet, eight inches, and a length of seventeen feet, nine and three-eighths inches, ninety-six four and one-half inch openings or holes 55 are utilized to receive the lower ends of the exhaust tubes 53. The openings 55 are arranged in the pattern shown to provide eight rows of twelve openings 55 in each row. Likewise, the top plate 49 is provided with openings 56 (FIGURE 5) which align themselves with the openings 55 in the lower plate 50.

The locations of the tubes 53 are determined to provide effective distribution of flow of supply air, to obtain substantially uniform exit flow of spent air from all areas, and to reinforce the plate members 49 and 50 to avoid deflection due to pressures of air within the chamber 48.

As also appears in FIGURE 2, the bottom impingement plate 50 is provided with a plurality of nozzle openings 57, and while for ease of illustration certain of the openings 57 have been eliminated in FIGURE 2, it should be understood that these openings are spaced in the pattern shown entirely across the length and width of the plate 50. Illustratively, the nozzle openings 57 are placed on three inch centers, and 2,176 openings are used, arranged in a pattern of thirty-two rows with sixty-eight openings in each row. While not illustrated, the equilateral triangular arrangement of holes 57 is preferably skewed approximately 5° with respect to the direction of web travel.

The nozzle orifices 57 are desirably rounded entrance openings as appears in FIGURE 6. It may be observed therefrom that each nozzle opening is defined by an inwardly flared throat portion 58 to provide a rounded-approach orifice as understood by those skilled in the art. It has been found that the illustrated flared configuration reduces orifice losses and permits high velocity jets of air to operate to scrub away the surface film of saturated moisture vapor traveling with the paper web W. Further, the flared nozzles promote a cyclonic turbulence between the air jets issuing from the openings 57, this turbulence being indicated generally in the directions of the arrows applied to FIGURE 6.

Experience has further demonstrated that the most desirable results are obtained by relatively close control over the diameter of the openings 57, measured between the points "a" and "b," and over the ratio of area of the openings 57 to total area of the plate 50. Specifically, the desirable range of diameters of the openings 57 is

between one-quarter and five-eighths inch with an optimum diameter of three-eighths inch at present being preferred. A ratio of hole or open area to total area of between one and three percent is preferred, and most preferably 1.5% is the optimum in work performed to date.

The thickness of the bottom impingement plate 50 is presently preferred to be one-quarter inch, and the holes or openings 57 therein may be either extruded or drilled, the latter technique providing a plate having the advantage of better strength and rigidity. The preferred spacing of the exposed surface of the plate 50 from the surface of the web W traveling about the drying cylinder 11c is one inch, when the hole diameter and ratio of hole area to total area are within the suggested limits. This spacing appears at present to provide optimum heat transfer and drying rate in accordance with the equation

$$h = CP^n$$

where:

h =heat transfer coefficient in B.t.u. per hour per square foot per degree Fahrenheit,

C =coefficient depending upon hole size and spacing,

P =the pumping power required to deliver the air and

n =an exponent approximately equal to 0.23.

Pursuing the above equation in work performed to date, it has been found that the coefficient C reaches a maximum value when the lower impingement plate 50 is one inch from the web W, and when the hole diameter is three-eighths inch and the open area is 1.5% of total area.

Referring now again to FIGURES 4 and 5, it will be observed that the inclined wall portions 29 and 30 of the hood outer wall support thereon relatively short length heater ducts 60 and 61, and of course, each hood section 20a and 20b is equipped with a pair of heater ducts. Gas heaters of the fire tube type may be substituted. The ducts 60 and 61 are essentially identical, and each is passaged at opposite ends to communicate the exhaust air chamber 22 and particularly the exhaust air tubes 53 with the exhaust air conduit 28 leading to the fans 42. Each heater conduit mounts at the lower end filter means 62 to prevent the passage of foreign materials such as paper bits, dust and the like to heater means 63 within each conduit 60 and 61 or to the fan means 42. The heater means 63 may take the form of steam coils, as shown.

The interior of each heater duct 60 and 61 communicates with the central tubular exhaust air conduit leading to the fans 42 by provision of passages 28a (FIGURE 5) at circumferentially spaced locations along the exhaust conduit 28. As appears in FIGURE 4, the total length of each heater duct 60 or 61 is less than the axial length of the insulated exhaust conduit 28 so that uninterrupted wall portions of the conduit 28 exist outwardly of opposite ends of the duct 60 and 61. Of course, communication between the heater conduits 60 or 61 and the exhaust air conduit 28 could be effected in different ways, however, the illustrated arrangement of interrupting the wall of the conduit 28 has proven quite effective in practice.

When the fan means 42 in each hood section 20a and 20b are operated, and the heater means 63 energized, high velocity-temperature air flow paths are provided in the directions indicated by the arrows to which the numeral 65 has been applied. The heated air passes downwardly or radially inwardly through the air supply conduits 47 and is diverted by the baffle means 52 in opposed directions both axially of the length of the drying cylinder 11c and circumferentially thereof generally within the limits of each hood section as defined by the wall sections 29a and 31a thereof. In this regard, it should be emphasized that the upright or radially extending exhaust tubes 53 received in the spaced plate means 49 and

50 effectively baffle and distribute the supply air to equalize the high velocity air flow, so that the delivery from the nozzle openings 57 in the bottom impingement plate 50 to the web is at all times uniform. As well, the exhaust tubes 53 provide a high degree of structural stiffness for the air supply chamber 48 to permit a continuous crosswise and longitudinal plenum. In addition, the exhaust tubes provide for uniform distribution of the discharge of the spent air from the zone between the drying cylinder 11c and the bottom impingement plate 50.

The heated supply air moves in the directions indicated by the arrows 65 from the supply conduits 47 to between the plates 49 and 50, issuing at high velocities through the rounded entrance orifices 57 to impinge upon the moist paper web W so as to penetrate the boundary film layer of vapor which adheres to the paper web, and which normally diminishes the effect of drying by vapor contact. The moisture-bearing or spent air is then withdrawn under action of the fan means 42 radially outwardly or upwardly through the exhaust tubes 53, following the path indicated by the arrows to which the numeral 66 has been applied. It may be observed that the moisture-bearing air is withdrawn through the exhaust tubes 53 toward the heater conduits 60 and 61 and through said

20 conduits to the passages 28a in the axially extending exhaust air conduit 28 communicating with the fan housings 45 and 46a. As was noted, a portion of the spent air may be exhausted through the opening 33, and by means of the access opening 29c, make-up air may be added to the moving air stream to maintain a proper balance in the recirculating air system.

It may be found necessary upon occasion to clean paper bits and the like from the air discharge chamber 48. For this purpose, the opposite end walls 26 and 27 of 35 each hood section 20a and 20b may be passaged as at 70 (FIGURES 3 and 4) to permit access to the space between the plate means 49 and 50.

The hood sections 20a and 20b are hingedly connected to permit raising and lowering of the hood sections when 40 it is desired to obtain access to the space between the bottom impingement plate 50 and the circumference of the drying cylinder 11c. Such access may be desired when the paper web W is being threaded onto the drying cylinder, either during initial start-up or following a sheet break. The hinge means for this purpose comprises a pair of hinge portions 71 and 72 welded or otherwise secured to the hood wall sections 31a, the hinge portions 71 and 72 being connected by pin means 73 providing a pivot point for the hinge sections 20a and 20b.

50 To effect a raising or lowering action of the hood sections 20a and 20b about the hinge point 73, various types of actuating means may be employed. A first form appears in FIGURES 3 and 4, and comprises bracket means 75 at opposite ends of the hood sections and supported upon frame structure 76 mounting the drier cylinder 11c through suitable bearing structure to be later noted. Each of the bracket means at opposite ends of the hood sections 20a and 20b receives pin means 77 to which is connected a link member 78, the opposite end of which receives pin means 79 to connect the link member 78 to one end of a threaded rod member 80, forming a part of screw jack means generally designated by the numeral 81.

65 The screw jack means 81 further includes a suitable housing 82, and within the housing is a pair of fixed flange portions 83 and 84. The screw rod member 80 is threaded for meshing engagement with sprocket means 85 mounted upon shaft means 86 supported by the screw jack housing 82. The sprocket means 85 has trained thereabout chain means 87, which also wraps sprocket means 88 carried upon shaft means 89 extending generally entirely along the length of the drying cylinder 11c.

70 It may now be observed that when a rotative force is applied to the sprocket means 88, the sprocket means 85 is caused to rotate in engagement with the screw member

80, causing linear movement of the rod member 80 relative to the housing flange portions 83 and 84. As the rod member 80 moves linearly, as in a raising action, the link member 78 connected to the rod member 80 swings about a fixed pivot 77, pivoting the hood sections 20a and 20b connected to the pin means 79 about the hinge point 73. Of course, the reverse action occurs during a lowering action.

In substitution for the screw jack means just described, hydraulic or pneumatic means may be employed. Referring now to FIGURE 7, the frame structure 76 may mount at opposite ends thereof bracket means 90 to which is connected by pin means 91 a link member 92 connected at its opposite end by pin means 93 to a piston 94 reciprocal within a cylinder 95 connected to the frame structure 76 by pin means or the like 96. Actuation of the cylinder 95 causes reciprocation of the piston 94 therein swinging the hood section 20a connected to the pin means 93 about the pivot point 91 upon the hinge point 73. In the arrangement of FIGURE 7, as well as with the screw jack means of FIGURES 3 and 4, it is important to note that the link members 92 or 78 therein perform an effective latching action during hood raising. More specifically, when the link arm 78 is raised by the screw jack means 81, or the link arm 92 raised by the piston means 84, and the respective links are on line with an imaginary line extending between the hinge point 72 and either the pin means 77 or 91, a stable linkage is provided and no further means are required to maintain the hood sections 20a and 20b in raised positions. In other words, the hinge portions 71 and 72 connecting the hood sections remain in elevated positions without the requirement for auxiliary support or latch means. The important advantage of this is that the hood sections can be raised or lowered much more quickly upon demand than would be the case if auxiliary fastening or safety devices were employed, which necessarily must be released either manually or automatically.

Another form of actuating means for effecting a raising or lowering action of the hood sections 20a and 20b appears in FIGURE 8, to which reference is now made. The frame structure 76 mounts bracket means 97 receiving pin means 98 for connecting a lever arm 99 to the bracket member 97 for pivotal movement thereon. The bracket member 99 generally centrally thereof is connected to the hood section 20a by fixed pin means 100, while at the end of the lever arm 99 opposite the pin connection 98 the lever arm receives pin means 101 to provide a connection with piston means 102 reciprocal within an actuator cylinder 103 fixedly connected to the frame structure 76, as at 104. Quite clearly, the cylinder 95 of FIGURE 7 and the cylinder 103 of FIGURE 8 may be either of the pneumatic or hydraulic type. And of course, the actuating means of FIGURES 7 and 8 are provided at both ends of each hood section 20a and 20b.

The various forms of hood elevating and lowering means described in connection with FIGURES 3, 4, 7 and 8 may be under the control of the machine operator, and as well, the actuating means may be responsive to web break detection means in the manner now known to the art. More specifically, upon occasion of a sheet break, it is desirable to effect a rapid raising action of the hood sections and essentially simultaneous stopping of the fan means to prevent broken pieces of the web from passing into the heating means, or at least jamming the nozzle structure. Accordingly, the described actuating means may be electrically connected through suitable circuitry to known web break detection means, and the same can be the case with respect to the motor means 36 in control of the fan means 42.

It should be observed that by the particular construction of air discharge 48 and tubular exhaust means 53 therein the heater means 63, fan means 42 and drive means 36 therefor, filter means 62 and recirculating duct-work can now all be packaged within the hood itself, pro-

5 ducing a unit having as an important advantage minimum use of insulation and minimum heat losses. The insulation 32 employed in the exhaust housing portion 22 has been earlier noted, and may now be seen to be minimum in amount. As well, it is desirable in order to conserve the heat energies that the exhaust tubes 53 receive thereon insulating sleeves or jackets 105, as appears in FIGURES 4 and 5. However, it is apparent that since the length and diameter of each exhaust tube 53 is at the minimum required for effective air circulation, the insulation sleeves 105 need not be excessively great in wall thickness.

and spaced on opposite sides of said hinge pin, equal distances from the axis of said hinge pin,

- (h) pivot pins pivotally connecting said link members to said hood sections adjacent the free ends thereof,
- (i) said threaded extensible power members having pivotal connection with said hood sections coaxial with the axes of said pivot pins connecting said link members to said hood sections and having sufficient travel to position the axes of said pivot pins upwardly beyond lines extending through the pivotal axis of said hinge pin and the axes of connection of said link members to said supporting frame structure, and thereby cooperate with the over-center positions of said link members to provide a self-locking structure locking said hood sections in elevated relation with respect to said drying cylinder.

2. A dryer in accordance with claim 1 wherein said threaded extensible power members are mounted on said supporting frame structure inwardly of the inner margins of said hood sections and are outwardly and upwardly
